UNITED STATES PATENT OFFICE

109,899

DESIGN FOR A BEAM PROJECTOR

Anthony L. McCabe, Reading, Mass.

Application March 26, 1938, Serial No. 76,104

Term of patent 3½ years

To all whom it may concern:

Be it known that I, Anthony L. McCabe, a citizen of the United States residing at 320 West Street, Reading, in the county of Middlesex and Commonwealth of Massachusetts, have invented a new, original, and ornamental Design for a Beam Projector, of which the following is a specification, reference being had to the accompanying drawing, forming a part thereof, in which

The figure is a view in side elevation of a beam projector showing my new design, the upper portion thereof being shown conventionally in dotted lines. The projector is circular in cross section.

I claim:

The ornamental design for a beam projector, substantially as shown and described.

ANTHONY L. McCABE.
